UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

MINING MACHINE.

Application filed July 16, 1923. Serial No. 651,829.

My invention relates to mining machines. An object of my invention is to provide an improved mining machine. Another object of my invention is to provide an improved compact feeding mechanism for a mining machine. A further object of my invention is to provide an improved compact feeding and feed controlling mechanism for a mining machine whereby the operation of such a machine is materially improved and the mechanism more compact and flexible to operate. These and other objects and advantages of my invention will, however, hereinafter more fully appear.

In the accompanying drawings I have shown for purposes of illustration one embodiment which my invention may assume in practice.

In these drawings,—

Fig. 1 is a plan view partially in section of a mining machine of the flexibly fed type. Fig. 2 is a side elevation, partially in section, of Fig. 1. Fig. 3 is a diagrammatic view showing the machine in operation in a room. Fig. 4 is a section on line 4—4 of Fig. 1.

In this illustrative construction I have shown a mining machine of the room and pillar type comprising a casing 1 slidable on its bottom 2 on the mine bottom and movable laterally by means of feeding means including advance and receding flexible feeding portions, herein flexible feeding members 3 and 4 in the form of wire ropes or cables, and having a cutter bar 5 rigidly secured within said machine frame provided with an endless cutter bit carrying cutter chain 6. The feeding means and the cutter chain are driven from a suitable motor 7, indicated by dotted lines in Fig. 2, which is controlled by suitable controlling and reversing mechanism, generally designated 8, through driving connections hereinafter described, and connected to a feed operating member and a take-up member, herein in the form of drums 9 and 10, and to a cutter chain driving sprocket 11 rotatable in bearings on a vertical axis beneath the rear end of the machine frame.

In describing my improved construction I will first describe the cutter chain driving mechanism. It will be noted that the armature shaft of the motor 7 is provided with a spur pinion 12 which in turn meshes with a spur gear 13 journaled on a stud 14 suitably carried by the frame 1. Suitably driven by the gear 13 is a bevel pinion 15 which meshes with a bevel gear 16 suitably journaled on a vertically disposed stud 17 on the rear end of the machine frame. The gear 16 is adapted to be connected at will to the sprocket 11 by means of a clutch mechanism 18 under the control of a shifter mechanism 19 operated by a lever 20 suitably carried on the advancing side of the machine frame.

Cooperating with this mechanism is the feeding mechanism. This mechanism is herein connected to and driven by an upstanding sleeve 21 rotatable with the bevel gear 16, the same being connected by a semi-permanent clutch 22 to a sleeve 23 having a worm 24 formed thereon, the sleeve 23 in turn being suitably journaled on a flanged bearing sleeve 25 and in bearings, not shown, carried within a removable cap member 26 carried by the top of the machine frame. This worm 24 meshes with a worm gear 27 disposed on a transverse horizontal axis. As shown, the worm 27 is keyed, as at 28, to a sleeve 29 which in turn drives, through a suitable planetary change speed mechanism generally designated 30, bevel pinions 31 and 32 suitably mounted on a shaft 33 secured within the machine frame and disposed coaxial with the axis of the worm gear 27. This planetary change speed mechanism may be of any approved form comprising for instance a central jaw clutch member 56, longitudinally slidable on and keyed to the shaft 33, adapted when in one extreme position of movement to engage a mating clutch member 57 keyed to an annular frame member 58 carrying sets of coaxial planet gears 59. One of the latter gears engages an internal gear 60 fixed to a rotatably mounted drum 61 while the other gear meshes with a second internal gear 62 fixed to a rotatably mounted annular member 63 having jaw clutch teeth 64 adapted to be engaged by the clutch member 56 when moved to its other extreme position. A friction band 35 is adapted to hold the drum against rotation when desired. In operation of the device when high speed is desired members 56 and 57 are engaged to thereby allow the worm to drive the planet gears 59 around the gear 60 which is held stationary by the friction band. Movement of the gears 59 thus causes rotation of the gear carrying frame 58 which being connected to the member 56 will directly drive the shaft 33 without in any way using the right hand planet gear. When a low speed is

desired members 56 and 64 are engaged and by holding the drum 61 the member 63 is rotated due to the different diameter of the planet gears. It will thus be seen that the 5 shaft 33 is adapted to drive the bevel pinions 31 and 32 at a predetermined fast or slow speed under the control of a shipper mechanism 34 and at variations of those speeds under the control of the brake band 35 which is 10 operated through suitable toggle mechanism 36 by a lever 37 carried on the advancing side of the machine frame. The bevel pinion 31 in turn meshes with a bevel gear 38 suitably journaled on a longitudinally disposed horizontal shaft 39 and which is adapted to be connected thereto by a jaw clutch 40 operated by a suitable shipper mechanism 41. Keyed to the shaft 39 is a spur pinion 42 which in turn meshes with an internal gear 43 suitably secured to the winding drum 10. It will be noted that this drum 10 is suitably journaled on a longitudinally disposed horizontal axis on the rear end of the machine frame 1. As shown, the bevel pinion 32 which is oppositely disposed with respect to the shaft 33, meshes with a bevel gear 45 adapted to be connected to a shaft 46, parallel with the shaft 39, by means of a jaw clutch 47 similar to the clutch 40. This shaft 46 drives a spur pinion 48 which in turn meshes with an internal gear 49 suitably secured to the winding drum 9 suitably journaled on the machine frame on an axis parallel with the axis of the drum 10. The exterior peripheries of the internal gears 35 43, 49 are provided with friction surfaces 51 and 52 under the control of brake bands 53 and 54 operated through suitable controlling mechanism by levers 55 carried on opposite sides of the machine frame, one of which is 40 shown in Fig. 2.

Cooperating with the feeding mechanism and engaging the drums 9 and 10 are the flexible feeding members or cables 3 and 4. Herein in the machine is shown adapted to cut from right to left and in this disposition of parts it will be noted that the advancing cable 3 extends from beneath the drum 9 around a horizontally disposed guide roll 56 and forward towards the front end of the machine and 45 around an idler sheave 57 laterally to the left hand rim, while the receding cable extends from beneath the drum 10 laterally to the right hand rib.

In the operation of my improved construction the machine is preferably, when unloaded from its transport truck, not shown, brought up to the face at the right hand rib to the position indicated in full lines in Fig. 3. The advancing cable 3 is then connected 55 to the left hand rib to an anchor jack A, while the receding cable 4 is connected to the right hand rib and an anchor jack B. The clutch 18 is then thrown in, thereby rotating the cutter chain and then by throwing in the jaw clutch 40 and throwing out the jaw clutch

47 the cutter bar is dumped in under the coal, the drum 10 winding in the cable 4 at a cutting speed while the drum 9 slowly pays it out under the control of the brake band 54, to a position indicated by dotted lines at the 70 right of Fig. 3. When in this position the clutch 40 is thrown out and the clutch 47 is thrown in and the machine may be straightened up and then cut transversely across the face of the room as indicated by the next 75 dotted line position at the left, the drum 9 winding in the cable 3 while the drum 10 pays out the cable 4 under control of brake band 53. When the machine reaches the left hand rib it may be inclined relative to the rib and backed out by suitable manipulation of the clutches 40 and 47 and the brake bands 53 and 54 in a well known manner and returned to its truck at a high or haulage speed. During the entire cutting operation 80 the speed of the drums 9 and 10 is entirely under the control of the planetary change speed mechanism 30. In the operation of my improved mechanism, it will be noted that by means of the clutch mechanism 18 the cutter 85 chain driving sprocket 11 may be rotated or caused to remain idle while the motor is running. Attention is also directed to the fact that by suitable manipulation of the lever 37 controlling the brake band 35 it is possible 90 to vary the speed of the feed drum 9 and the take-up drum 10 without disconnecting either of the same from the motor and that by means of the clutches 40 and 47 the drums may be rotated simultaneously or independently. It 95 will also be noted that when the drums are disconnected from the motor they may be controlled by the brake bands 53 and 54, thereby increasing the facility of operation of the machine. These and other advantages of 100 my improved construction will, however, be clearly apparent to those skilled in the art.

While I have in this application specifically described one form which my invention may assume in practice, it will be understood that 110 this form of the same is shown for purposes of illustration and that the invention may be modified and embodied in various other forms without departing from its spirit or the scope of the appended claims.

What I claim as new and desire to secure by Letters Patent is:

1. In a mining machine, a motor having its axis extending longitudinally of the machine, and feeding mechanism including relatively 120 rotatable winding members adapted to cooperate with flexible feeding means and rotatable on parallel horizontal axes lying in vertical planes parallel with the longitudinal axis of said motor, said members being disposed in the same transverse zone, and driving mechanism between said motor and said members.

2. In a mining machine, a longitudinally disposed motor, and feeding mechanism in- 130

- cluding relatively rotatable winding drums disposed on axes disposed longitudinally of said motor and means to drive said drums from said motor, said drums being disposed substantially in the same transverse zone. 5
3. In a mining machine, a motor, feeding mechanism including relatively rotatable feed controlling elements disposed at the same end of the machine on longitudinally extending parallel axes and each adapted to cooperate with flexible feeding means, and driving mechanism between said motor and said elements. 10
4. In a mining machine, a motor, feeding mechanism including relatively rotatable feed controlling elements disposed at the same end of the machine on longitudinally extending parallel axes and each adapted to cooperate with flexible feeding means, and variable speed driving mechanism between said motor and said elements. 15
5. In a mining machine, a motor extending longitudinally of the machine, feeding mechanism including a plurality of relatively rotatable feed controlling elements each adapted to cooperate with flexible feeding means and disposed at the rear end of the machine on axes parallel with the longitudinal axis of said machine, and means to drive each of said elements from the rear end of said motor at a plurality of predetermined speeds. 20
6. In a mining machine, a motor extending longitudinally of the machine, feeding mechanism including relatively rotatable feed controlling elements each adapted to cooperate with flexible feeding means and disposed at the rear end of the machine on axes parallel with the longitudinal axis of said machine, means to drive each of said elements from the rear end of said motor at a plurality of predetermined speeds, and means to vary said speeds. 25
7. In a mining machine, a motor feeding mechanism including relatively rotatable winding drums disposed side-by-side on parallel axes extending longitudinally of said motor and substantially in the same transverse zone, driving mechanism between said motor and drums to drive the latter, means to vary the speed of said driving mechanism, and means to control rotation of said drums. 30
8. In a mining machine, a frame having relatively rotatable feed operating and take-up members thereon each adapted to cooperate with flexible feeding means and rotatable on longitudinally extending parallel axes at the same end of the machine and having surfaces adapted to engage flexible feeding means, and guiding means disposed on each side of the axes of said feed operating and take-up members. 35
9. In a mining machine, a motor having its axis extending longitudinally of the machine, a feed operating member and a relatively rotatable take-up member each adapted to co- 40
- operate with flexible feeding means and disposed on longitudinal axes parallel with the axis of said motor, and driving mechanism for said members including variable speed planetary gearing common to both of said members. 45
10. In a mining machine, a frame, relatively rotatable feed operating elements each adapted to cooperate with flexible feeding means carried by said frame and disposed on parallel axes extending longitudinally of the machine, and driving mechanism between said motor and said feed operating elements including variable speed planetary gearing common to both of said elements. 50
11. In a mining machine, a frame, relatively rotatable feed operating elements carried thereby disposed on axes extending longitudinally of the machine and each adapted to cooperate with flexible feeding means, and driving mechanism between said motor and said elements including a variable speed mechanism common to both of said elements and disposed on a transverse axis. 55
12. In a mining machine, a motor, a feeding mechanism including relatively rotatable winding drums disposed on axes extending longitudinally of the machine, and driving mechanism therefor including frictionally controlled planetary gearing common to both of said drums. 60
13. In a mining machine, cutter chain driving mechanism, feeding mechanism therefor including a feed operating member and a relatively rotatable take-up member both disposed at the rear of the machine and on axes extending longitudinally of the machine and adapted to cooperate with flexible feeding means, planetary driving means for said members, and means to drive said members independently or simultaneously at variable speeds. 65
14. In a mining machine, a frame slidable on its bottom on the mine bottom during operation of the machine and carrying a motor, the axis of said motor being horizontal and extending longitudinally of the machine, feeding mechanism for feeding the machine bodily laterally over the mine bottom during the cutting operation including relatively rotatable winding members rotatable on axes disposed in upright planes parallel to the axis of said motor and on opposite sides of said axis, and means to drive said members at variable speeds including frictional means common to both of said members for controlling rotation thereof. 70
15. In a mining machine, a frame slidable on its bottom on the mine bottom during operation of the machine and carrying a motor, feeding mechanism for feeding the machine bodily laterally over the mine bottom during the cutting operation including a shaft, relatively rotatable winding drums rotatable on axes disposed in upright planes parallel to 75
- 80
- 85
- 90
- 95
- 100
- 105
- 110
- 115
- 120
- 125
- 130

the longitudinal axis of said machine and on opposite sides of said axis and angularly disposed to the axis of said shaft, and means to drive each of said drums at a plurality of predetermined speeds.

16. In a mining machine, a longitudinally disposed motor, and feeding mechanism including a feed operating member and a take-up member each adapted to cooperate with flexible feeding means and rotatable on laterally spaced longitudinally extending horizontal axes on the rear end of said machine.

17. The combination with a mining machine, of feeding mechanism therefor including relatively rotatable feed controlling members disposed at the same end of the machine and adapted to cooperate with flexible feeding means and rotatable about longitudinally extending parallel axes, and actuating means for said feeding mechanism including a worm disposed between the axes of and common to both of said members.

18. The combination with a mining machine, of feeding mechanism therefor including relatively rotatable feed controlling elements each adapted to cooperate with flexible feeding means and disposed at the same end of the machine and rotatable on longitudinally extending parallel axes, and actuating means therefor including driving mechanism disposed substantially in a zone between the axes of said members.

19. A mining machine having relatively rotatable feed controlling elements each adapted to cooperate with flexible feeding means and disposed at the same end of the machine and rotatable on longitudinally extending parallel axes, cutting mechanism, and actuating means therefor including a substantially vertical shaft and driving connections between said shaft and said members including a worm carried by said shaft.

20. A mining machine having feeding means therefor including a plurality of relatively rotatable feed controlling members each adapted to cooperate with flexible feeding means and disposed at the same end of the machine and rotatable on substantially longitudinally extending axes, actuating means therefor including a plurality of shafts also disposed substantially longitudinally of said machine, and a shaft common to each of said other shafts for driving the latter and angularly disposed relative thereto.

21. In a mining machine, a frame slideable on its bottom on the mine bottom during operation of the machine, cutting mechanism carried thereby including a cutter bar projecting from one end thereof, and feeding means for feeding the machine bodily laterally over the mine bottom during the cutting operation including a feed controlling member adapted to cooperate with flexible feeding means and rotatable about a horizontal

axis disposed at the end of the machine opposite from said cutter bar in a vertical plane extending longitudinally of the machine, driving means therefor including a shaft extending in the same general direction as the axis of said member, a second shaft disposed transversely of said plane, gears mounted directly on each of said shafts and meshing with each other, and a third shaft having its axis angularly disposed to the axes of each of said other shafts and gearing between said second and third shafts.

22. In a mining machine, a plurality of relatively rotatable feed controlling elements each adapted to cooperate with flexible feeding means rotatable on longitudinally extending axes and in substantially the same transverse zone, power means for selectively driving either of the same, and means for frictionally controlling either of said elements when the other is being power driven.

23. In a mining machine, a plurality of relatively rotatable feed controlling elements each adapted to cooperate with flexible feeding means and rotatable on substantially parallel axes extending longitudinally of the machine and disposed at the same end of the machine, and means for frictionally controlling each of the same including actuating means for said elements disposed in a single plane.

24. In a mining machine, feeding mechanism therefor including a plurality of relatively rotatable feed controlling elements each adapted to cooperate with flexible feeding means and disposed on parallel axes extending longitudinally of the machine at the same end of the machine, power means for driving each of the same, and frictional means for controlling the same independently or simultaneously.

25. In a mining machine, a horizontal motor, and feeding mechanism including relatively rotatable feed operating and controlling members each adapted to cooperate with flexible feeding means and disposed side-by-side on parallel axes disposed parallel with the longitudinal axis of said motor and in substantially the same transverse zone, and driving mechanism between said motor and members.

26. In a mining machine, a horizontal motor having its axis extending longitudinally of the machine, and feeding mechanism driven by said motor including relatively rotatable feed operating and controlling members each adapted to cooperate with flexible feeding means and disposed on axes parallel with the longitudinal axis of said motor and in substantially the same transverse zone.

27. In a mining machine, a horizontal motor, and feeding mechanism including relatively rotatable feed operating and controlling members each adapted to cooperate with

- flexible feeding means and disposed side-by-side on parallel axes disposed parallel with the longitudinal axis of said motor and at the same end of the machine, and driving mechanism between said motor and members. 5
28. In a mining machine, a motor having its axis of rotation extending longitudinally of the machine, a plurality of relatively rotatable feed operating and controlling members each adapted to cooperate with flexible feeding means and disposed on axes extending longitudinally of the machine and parallel with the axis of said motor, said members being disposed at the same end of the machine, and driving mechanism for said members including variable speed planetary gearing common to both of said members. 10
29. In a mining machine, a frame slidable on its bottom on the mine bottom during operation of the machine and carrying a motor, feeding mechanism for feeding the machine bodily laterally over the mine bottom during the cutting operation including relatively rotatable feed operating and controlling members each adapted to cooperate with flexible feeding means and rotatable on axes disposed at the same end of the machine in upright planes parallel to the axis of said motor and on opposite sides of said axis, and means to drive said members at variable speeds including frictional means common to both of said members for controlling rotation thereof. 20
30. In a mining machine, a longitudinally disposed motor, and feeding mechanism including relatively rotatable feed operating and controlling members rotatable on laterally spaced horizontal axes extending longitudinally of the machine and on the rear end of the machine and each adapted to cooperate with flexible feeding means. 35
31. In a mining machine, a plurality of relatively rotatable feed controlling elements each adapted to cooperate with flexible feeding means and rotatable on parallel axes extending longitudinally of the machine and in substantially the same transverse zone at the same end of the machine, power means for selectively driving either of said elements, and means for frictionally controlling either of said elements when the other is being power driven. 45
32. In a mining machine, a motor, and feeding means driven by said motor including plural predetermined speed transmission means frictionally controlled at each of said predetermined speeds, and a plurality of relatively rotatable feed operating and controlling members driven thereby disposed at the same end of the machine and rotatable on parallel axes extending longitudinally of the machine, said members each being adapted to cooperate with flexible feeding means. 55
33. In a mining machine, a frame slidable on its bottom on the mine bottom during operation of the machine and carrying a motor, and feeding means for feeding the machine bodily laterally over the mine bottom during the cutting operation including plural speed epicyclic gearing driven thereby disposed with its axis of orbital movement in a horizontal plane, a plurality of relatively rotatable feed operating and controlling members each adapted to cooperate with flexible feeding means and rotating on parallel axes 70 lying in vertical planes extending longitudinally of the machine, and means for connecting said members to said gearing. 75
34. In a mining machine, a frame slidable on its bottom on the mine bottom during operation of the machine and carrying a motor, and feeding means for feeding the machine bodily laterally over the mine bottom during the cutting operation including plural predetermined speed epicyclic gearing driven thereby disposed with its axis of orbital movement in a horizontal plane, and a feed operating member adapted to cooperate with flexible feeding means and rotating on an axis lying in a plane parallel to a plane perpendicular to the axis of said orbital movement, and means for connecting said member to said gearing. 80
35. In a mining machine, a frame slidable on its bottom on the mine bottom during operation of the machine and carrying a motor, and feeding means for feeding the machine bodily laterally over the mine bottom during the cutting operation including plural predetermined speed epicyclic gearing driven thereby disposed with its axis of orbital movement in a horizontal plane and extending transversely of the machine, a feed operating member adapted to cooperate with flexible feeding means and rotating on an axis lying in a plane parallel to a plane perpendicular to the axis of said orbital movement, and means for connecting said member to said gearing. 90
36. In a mining machine, a motor, and feeding means driven by said motor including plural predetermined speed transmission means frictionally controlled at each of said predetermined speeds, and a plurality of relatively rotatable feed operating and controlling members driven thereby rotating on parallel axes extending longitudinally of the machine at the same end of the latter, said members each being adapted to cooperate with flexible feeding means. 100
37. In a mining machine, a horizontal motor having its axis extending longitudinally of the machine, and feeding means driven from the rear end of said motor including plural predetermined speed transmission means frictionally controlled at each of its predetermined speeds, and a plurality of relatively rotatable feed operating and controlling members disposed at the rear end of the machine each rotating on a horizontal 110

axis extending longitudinally of the machine and each adapted to cooperate with flexible feeding means.

38. In a mining machine, a horizontal motor having its axis extending longitudinally of the machine, and feeding means driven from the rear end of said motor including plural predetermined speed transmission means frictionally controlled at each of its predetermined speeds, and a plurality of relatively rotatable feed operating and controlling members rotating on parallel horizontal axes extending longitudinally of the machine and each adapted to cooperate with flexible feeding means.

39. In a mining machine, a horizontal motor having its axis extending longitudinally of the machine, and feeding mechanism driven from the rear end of said motor including a feed operating member and a relatively rotatable controlling member each adapted to cooperate with flexible feeding means and rotating on a horizontal axis extending longitudinally of the machine, said members being at the rear end of the latter.

40. In a mining machine, a motor, and feeding means driven by said motor including plural predetermined speed epicyclic gearing frictionally controlled at each of its predetermined speeds, a plurality of relatively rotatable feed operating and controlling members each adapted to cooperate with flexible feeding means and rotating on parallel horizontal axes extending longitudinally of the machine at the same end of the latter, and means for connecting said members to said gearing.

41. In a mining machine, a motor, and feeding means driven by said motor including a plural predetermined speed epicyclic gear mechanism frictionally controlled at each of its predetermined speeds and disposed with its axis of orbital movement in a transverse horizontal plane, a plurality of relatively rotatable feed operating and controlling members each adapted to cooperate with flexible feeding means and rotating on parallel horizontal axes extending longitudinally of the machine, and means for connecting said members to said gear mechanism.

42. In a mining machine, a frame slideable on its bottom on the mine bottom during operation of the machine and carrying a motor, cutting mechanism driven thereby including a cutter bar projecting from one end of the machine, and feeding means driven by said motor for feeding the machine bodily laterally over the mine bottom during the cutting operation including a plural predetermined speed epicyclic gear mechanism frictionally controlled at each of its predetermined speeds and disposed with its axis of orbital movement in a horizontal plane and extending transversely of the machine, a feed operating member adapted to cooperate with

flexible feeding means rotating on an axis lying in a plane parallel to a plane perpendicular to the axis of said orbital movement and disposed at the end of the machine opposite from said cutter bar, and means for connecting said member to said gear mechanism.

43. In a mining machine, a motor, feeding mechanism including a feed operating member and a relatively rotatable take-up member each adapted to cooperate with flexible feeding means and rotatable on horizontal axes disposed at the same end of the machine, said axes lying in upright planes parallel to the longitudinal axis of said machine and on opposite sides of said axis, and a vertically disposed driving worm therefor.

44. In a mining machine, a frame slideable on its bottom on the mine bottom during operation of the machine and carrying a motor, cutting mechanism driven by said motor including a forwardly projecting cutter bar, and flexible feeding means for feeding the machine bodily laterally over the mine bottom during the cutting operation including advance and receding flexible feeding portions extending laterally in opposite directions from opposite ends of said frame, relatively rotatable feed operating members disposed at the same end of the machine on parallel axes lying in parallel vertical planes extending longitudinally of the machine and adapted to cooperate with said feeding portions respectively, and a plural speed driving mechanism between said motor and said members and having a plurality of speeds frictionally controlled at each speed.

45. In a mining machine, a motor, and feeding means driven thereby comprising frictionally controlled planetary gearing, and a feed operating member driven thereby adapted to cooperate directly with flexible feeding means and rotatable on a horizontal axis extending longitudinally of the machine.

46. In a mining machine, a motor, plural speed epicyclic gearing driven thereby, a plurality of independently operable feed operating and controlling members adapted to cooperate with flexible feeding means and rotating on parallel axes lying in vertical planes extending longitudinally of said machine, and means for connecting said members to said gearing.

47. In a mining machine, a motor, plural speed epicyclic gearing driven thereby, a plurality of independently operable feed operating and controlling members adapted to cooperate with flexible feeding means and rotating on parallel horizontal axes extending longitudinally of said machine, and means for connecting said members to said gearing.

48. In a mining machine, a motor, and feeding means driven by said motor including plural predetermined speed transmission

- means frictionally controlled at each of its predetermined speeds and comprising a terminal element transmitting power at each speed, and a plurality of independently operable drums rotatable on parallel horizontal axes extending longitudinally of the machine.
49. In a mining machine, a motor, and feeding means driven by said motor including plural predetermined speed transmission means frictionally controlled at each of its predetermined speeds and comprising a terminal element transmitting power at each speed, and a plurality of independently operable drums driven by said terminal element 15 rotatable on parallel axes in a common zone transverse to the drum axes and of the width of a single drum.
50. In a mining machine, a motor, and feeding mechanism driven by said motor including plural predetermined speed transmission means frictionally controlled at each of its predetermined speeds and comprising coaxial fast and slow speed clutches, a driving terminal element selectively driven 20 through said clutches, and drums driven by said element rotatable on parallel axes extending longitudinally of the machine.
51. In a mining machine, a motor, and feeding means driven thereby comprising variable speed transmission mechanism including coaxial driving elements respectively 25 effecting different speeds when operative, clutch means for rendering said driving elements selectively operative as the effective driving element, said clutch means disposed between said driving elements, and a plurality of feed drums rotatable on spaced axes extending longitudinally of the machine.
52. In a mining machine, a motor, plural speed epicyclic gearing driven thereby and having incorporated therewith means whereby the same is frictionally controlled at each speed, a plurality of feed operating and controlling members adapted to cooperate with 35 flexible feeding means and rotating on parallel axes lying in vertical planes extending longitudinally of said machine, and means for connecting said members to said gearing.
53. In a mining machine, a motor, plural speed epicyclic gearing driven thereby and having incorporated therewith means whereby the same is frictionally controlled at each speed, a plurality of feed operating and controlling members adapted to cooperate with flexible feeding means and rotating on parallel horizontal axes extending longitudinally of said machine, and means for connecting said members to said gearing.
54. In a mining machine, a motor, and feeding means including plural speed epicyclic gearing driven thereby and having incorporated therewith means whereby the same is frictionally controlled at each speed, a plurality of relatively rotatable feed operating and controlling members adapted to cooperate with flexible feeding means and rotating on axes each lying in a vertical plane extending longitudinally of the machine, and means for connecting said members to said gearing.
55. In a mining machine, a motor, a plurality of feed operating members adapted to cooperate with flexible feeding means and rotatable on parallel axes extending longitudinally of the machine, and transmission means between each of said members and said motor including planetary gearing.
56. In a mining machine, a motor, feed operating members adapted to cooperate with flexible feeding means and rotatable on parallel axes extending longitudinally of the machine, cutting mechanism, transmission means between said motor and said feed operating members, and means for driving said cutting mechanism from said transmission means.
57. In a mining machine, a motor, feed operating members adapted to cooperate with flexible feeding means and rotatable on parallel axes extending longitudinally of the machine, cutting mechanism, transmission means between said motor and said feed operating members, and means including a clutch for driving said cutting mechanism from said transmission means.
58. In a mining machine, a motor, feed operating members adapted to cooperate with flexible feeding means and rotatable in the same vertical transverse plane on axes extending longitudinally of the machine, cutting mechanism, transmission means between said motor and said feed operating members, and means for driving said cutting mechanism from said transmission means which drives said feed operating members.

In testimony whereof I affix my signature.
CHARLES F. OSGOOD.

CERTIFICATE OF CORRECTION.

Patent No. 1,704,667.

Granted March 5, 1929, to

CHARLES F. OSGOOD.

It is hereby certified that error appears in the printed specification of the above numbered patent requiring correction as follows: Page 3, line 43, claim 7, after the word "motor" insert a comma; and that the said Letters Patent should be read with this correction therein that the same may conform to the record of the case in the Patent Office.

Signed and sealed this 16th day of April, A. D. 1929.

(Seal)

M. J. Moore,
Acting Commissioner of Patents.
